UNITED STATES PATENT OFFICE.

JOHN CEDERSTROM, OF BUFFALO, NEW YORK, ASSIGNOR TO THE UNITED STATES AERATING FOUNTAIN COMPANY, OF SAME PLACE.

DESIGN FOR A SHIELD OR GUARD FOR SIPHONS OR SIMILAR ARTICLES.

SPECIFICATION forming part of Design No. 32,397, dated March 27, 1900.

Application filed February 9, 1900. Serial No. 4,687. Term of patent 14 years.

To all whom it may concern:

Be it known that I, JOHN CEDERSTROM, of Buffalo, New York, have invented and produced a new and useful Design for a Shield or Guard for Siphons or Similar Articles, which design is fully set forth in the following specification.

Figure 1 of the drawings is an elevation of a guard or shield for siphons or similar articles, and Fig. 2 is a transverse section of the same.

As shown in the drawings, the leading or material features of my design are the substantially globular or spherical configuration of the shield and the openings therein that give what may be designated as a "gooseberry" effect. More particularly, A is the shield, and B B represents a series of openings therein separated by the meridional portions

a a of the shield A. The outline of each opening B is produced on the sides by the lines of these portions *a* curving gently into the ends *b b* to produce a well-balanced form for the openings and to present a pleasing appearance to the design as a whole.

Having thus described my invention, I claim—

The design for a shield or guard for siphons or similar articles, substantially as shown and described.

In testimony whereof I have signed this specification in the presence of two subscribing witnesses.

JOHN CEDERSTROM.
